UNITED STATES PATENT OFFICE.

JOSEPH C. STOCK, OF NEW YORK, N. Y.

SPRING BOOT.

Application filed August 7, 1924. Serial No. 730,562.

To all whom it may concern:

Be it known that I, JOSEPH C. STOCK, a citizen of the United States, residing at New York city, in the county of New York and State of New York, have invented certain new and useful Improvements in Spring Boots, of which the following is a specification.

This invention relates in general to covers for laminated springs, and particularly to the type of covers as used in connection with laminated automobile springs.

I am aware that it has been proposed to enclose the vehicle springs with flexible covering having for its object to protect the spring and the lubricant contained therein. The various methods used have attempted to cause the cover to fit snugly to the spring, at the same time prevent the lubricant from running out and to provide means for introducing the lubricant into the cover.

It has been found, however, in practice, that the covers do not always fit tightly and the edges which are laced or otherwise closed, do not meet, thereby allowing lubricant to leak out.

When the cover is made up of a plurality of pieces, it has been found that if the stitching gives way, the boot opens and no longer retains its function of maintaining the grease around the spring.

One of the objects of the present invention is the formation of the sides to accommodate the greater diameter of the spring clips, otherwise the boot has to be stretched into shape over the springs and is subjected to great strain. Without the formation of the sides as shown, there is possible leakage of grease from the boot.

Another object of the invention is to provide means at the ends of the cover to prevent leakage of grease.

A further object of the invention is to provide a spring cover that is exceptionally strong at the ends where the greatest strain occurs, thus obviating any possibility of stretching of the material and leakage of grease.

Still another object of the invention is to provide a cover formed to fit over the spring.

Another object of my invention is to provide reinforcing means at the top of the spring boot where the greatest wear occurs.

A still further object is to provide a construction of spring boot so made that if the forming stitches give way the boot will still be operative.

The present invention has further advantages in that it can be put on quickly and it is not necessary to soak the cover before attaching to the spring. This soaking and stretching is a tedious operation. The lubricant can be placed inside at the top of the cover and, therefore, it is not always required to separately grease the springs before putting the boot on, thereby saving time.

With these and other objects in view which may be incident to my improvements, the invention consists in the parts and combinations to be hereinafter set forth and claimed, with the understanding that the several necessary elements comprising my invention, may be varied in construction, proportions and arrangement, without departing from the spirit and scope of the appended claims.

In order to make my invention more clearly understood, I have shown in the accompanying drawings means for carrying the same into practical effect without limiting the improvements in their useful applications to the particular constructions, which for the purpose of explanation, have been made the subject of illustration.

In the drawings:—

Figure 1 is a perspective view showing a cover partially laced to a spring;

Fig. 2 is a sectional view along the line 2—2 of Fig. 1;

Fig. 3 is a bottom view showing the boot in place on the narrow end of the spring;

Fig. 4 is a bottom plan view of the form shown in Fig. 1, with the sides extended;

Fig. 5 is a sectional view along the line 5—5 of Fig. 1:

Fig. 6 is a sectional view along the line 6—6 of Fig. 4;

Fig. 7 is a top plan view showing a modification of the form shown in Fig. 1;

5 Fig. 8 is a top plan view showing another modification of the form shown in Fig. 1.

Referring to the drawings, and more particularly to Fig. 1, A is a spring built up 10 of laminated leaf springs having the usual form of springs clips b and c. Over the spring A is placed a cover or boot 1, having side members 2 formed with lobes 3, provided with suitable closure means, to be 15 hereinafter described.

When the boot 1 is placed over the spring A, the lobes 3 formed on the side members 2 accommodate the greater diameter of the spring clips b and c.

20 The boot 1 has a top 5 (Fig. 5) shaped by means of longitudinal ribs 6, the ribs being stitched at 7, as shown in Figs. 5 and 6. The ribs 6, besides serving as a shaping means for the top 5 of the boot 1, 25 give a double thickness edge. The stitches 7 may come out and the boot will still be operative, maintaining its position around the spring and preventing leakage of the lubricant.

30 At the extremities and on the inside of the boot are attached pieces of compact and flexible material 8, such as felt or other suitable material, the material forming a flap 9 which functions to retain the lubricant

35 10 (Fig. 2) within the boot. One of the side members 2 has an apron 11 fastened to its outer edge 12. The apron acts as a retainer for the lubricant 10 and also serves to reinforce the joint 13 when the 40 boot is laced to the spring. At the time the boot is placed in position around the spring, the apron or flap 11 is folded back upon itself, as shown in Fig. 5, which indicates the position of the apron 11 after the boot 45 is fastened in place.

At the extremities of the boot on the outside are attached straps 14. The straps are stitched to the side members 2 and the top 5, serving to reinforce and strengthen the 50 ends of the boot. This construction positively prevents stretching of the flexible cover with consequent leakage of the grease.

The side members 2 are provided with eyelets 15 for the lacing 16. The eyelets 55 on the side member 2 to which the apron or flap 11 is attached, serve as a fastening means to attach the apron 11 to the side member.

A modification of the form in Fig. 1 is 60 shown in Fig. 7, which shows a boot or cover having one pair of lobes 3 on the side members 2. This form is used with a spring having only one spring clip.

Referring to Fig. 8, which shows another 65 modification of the form shown in Fig. 1,

instead of forming the side members 2 with lobes 3, the longitudinal ribs 6 are formed with bulges or humps 17 to give the formation which will accommodate the greater diameter of the spring clip. 70

The boot or cover as described is easily and quickly applied to the spring. Since it is already formed to fit the configuration of the spring, it is not necessary to wet or soak the boot in water before attaching it. 75 This saves a great deal of time for a mechanic in attaching the cover to the springs of a single car.

The grease can be applied to the cover before the cover is placed around the spring 80 and in many instances it is not necessary to apply grease to the spring before putting the cover in place. A cover applied in the above manner not only saves time, but also conserves the lubricant. The reinforcing 85 straps at the extremities prevent the cover from stretching at points where the greatest possibility of leakage of grease occurs.

While I have shown and described the preferred embodiment of my invention, I 90 wish it to be understood that I do not confine myself to the precise details of construction herein set forth, by way of illustration, as it is apparent that many changes and variations may be made therein, by 95 those skilled in the art, without departing from the spirit of the invention, or exceeding the scope of the appended claims.

I claim:—

1. A spring protecting cover comprising 100 a covering member of a single piece of material having its sides formed with lobes to accommodate the greater diameter of the spring clips, said cover being adapted to fit around the spring.

2. A spring protecting cover comprising 105 a covering member of a single piece of material having compact and flexible material attached at the ends and a felt apron on the inside of the cover at each end to prevent leakage of grease and rows of stitching to conform the cover to the width of the spring clip.

3. A spring protecting cover of the character described comprising a covering member of a single piece of material folded and stitched upon itself to conform the cover to the width of the spring clip, strips of felt sewed to the ends forming an apron on the inside of said cover to prevent leakage of grease and a reinforcing strap at each end of the cover on the outside. 115

4. A spring protecting cover comprising 120 a covering member of a single piece of material having strips of felt sewed to the ends on the inside of said cover to form an apron, and a flap attached to one of the side edges by the lacing means.

5. A spring protecting cover comprising 125 a covering member of a single piece of ma-

terial, strips of felt sewed to the ends on the inside of the cover to form an apron, and a flap attached to one of the side edges of said cover by means of eyelets, on the 5 lacing hooks.

6. A spring protecting cover comprising a cover member of a single piece of material having its sides formed with lobes to accommodate the greater diameter of the 10 spring clips, and rows of stitching to con-

form the boot to the width of the clips and spring.

7. A spring protecting cover comprising, a cover member of a single piece of material and rows of stitching to conform the cover 15 to the width of the spring and clip.

In testimony whereof I affix my signature.

JOSEPH C. STOCK.
